UNITED STATES PATENT OFFICE.

JOSEPH F. CAMPBELL, OF MCKEESPORT, PENNSYLVANIA, ASSIGNOR TO PITTSBURGH STEEL FOUNDRY, OF PITTSBURG, PENNSYLVANIA, A CORPORATION OF PENNSYLVANIA.

ANNEALING-BOX.

No. 908,949.

Specification of Letters Patent.

Patented Jan. 5, 1909.

Application filed May 7, 1908. Serial No. 431,310.

To all whom it may concern:

Be it known that I, JOSEPH F. CAMPBELL, of McKeesport, in the county of Allegheny and State of Pennsylvania, have invented 5 certain new and useful Improvements in Annealing-Boxes, of which the following is a specification.

My invention relates to a new and improved annealing box, and more particularly to a cast-metal annealing box consisting of an integral structure.

The prime object of the present invention is to provide a stronger and more durable annealing box than boxes of this class now 15 so generally used; and I accomplish these ends by providing a new and improved form of roof and strengthening means therefor.

In the accompanying drawing, which 20 Figure 1 is a perspective view of an annealing box constructed in accordance with my invention; and Fig. 2 a transverse section thereof.

As illustrated and as preferred the annealing box comprises an integral cast-metal 25 structure having side-walls 1, formed with horizontal strengthening and stiffening ribs 2, end-walls 3, also formed with horizontal ribs 4; and a roof 5. The box is also provided with the usual trunnions 6.

Annealing boxes of the class to which my invention relates have heretofore been constructed with the side and end-walls and with a flat-roof, or with an arched or convex roof. As it is well known, these boxes, 35 in use, are subjected to intense and long continued heat which causes the roof to sag and the side walls to be bulged outwardly, thus distorting the box, and, in a comparatively short time, rendering the box useless for annealing purposes.

I am aware that webs, tie rods and struts have been provided on the interior of the

box designed to prolong the life of the same or to prevent the evil results above mentioned, but these means have not proven entirely satisfactory.

A characteristic and important feature of my invention is the concaved roof 5. By providing the concaved roof, I am enabled to prevent the upper portions of the side-walls from being pushed outwardly or bulged, when the box is subjected to the intense heat above mentioned.

In addition to the parts mentioned the box is provided with end-ribs 7 and with intermediate ribs or members 8 all formed on the exterior of the roof.

The form of roof illustrated co-operates with the members 7 and 8 to form pockets or receptacles adapted to receive sand or gravel when it is desired to cover the roof of the box with such material.

What I claim is:

1. An annealing box having side and end-walls, and a concaved roof all comprising an integral structure.

2. An annealing box having side and end-walls, a concaved roof, and strengthening members on the exterior of the roof all comprising an integral structure.

3. A cast-metal annealing box consisting of an integral structure having side and end-walls, a concaved roof, and ribs formed on the exterior of the roof.

4. A cast-metal annealing box consisting of an integral structure having side and end-walls, a concaved roof, and end and intermediate projections formed on the exterior of the roof.

In testimony whereof I affix my signature in presence of two witnesses.

JOSEPH F. CAMPBELL.
